UNITED STATES PATENT OFFICE.

MARTIN T. HOWARD, OF CLARENDON, TEXAS.

ANT-TRAP.

No. 884,928.

Specification of Letters Patent.

Patented April 14, 1908.

Application filed December 9, 1907. Serial No. 405,811.

To all whom it may concern:

Be it known that I, MARTIN T. HOWARD, a citizen of the United States, residing at Clarendon, in the county of Donley, State of Texas, have invented certain new and useful Improvements in Ant-Traps; and I do hereby declare the following to be a full, clear, and exact description of the invention, such as will enable others skilled in the art to 10 which it appertains to make and use the same.

This invention relates to a new and useful improvement in ant traps.

The object of my invention is to provide a 15 simple inexpensive sheet metal trap not having any movable parts.

In the accompanying drawings, I have shown in Figure 1 a perspective view of my trap, while, Fig. 2 shows a central sectional view of a trap embodying my invention.

In carrying out the object of my invention, I use a disk 1 of sheet metal provided with a central perforation α . Secured to this disk 1 which forms a base plate is a sheet metal 25 frusto-conical member 4, the enlarged end of which extends upwardly as shown in Fig. 2 while the reduced end is of a size corresponding to the opening α , this frusto-conical member 4 being secured to the base plate 1 in the 30 manner disclosed in Fig. 2.

Secured to the base plate 1 is a sheet metal casing 2 also of frusto-conical form, this casing, however, not being inverted as is the one marked 4 and this casing 2 is provided with 35 a peripheral knife edged flange 5 and an inwardly extending horizontally disposed flange 3, said flange 3 and the upper termination of the frusto-conical member 4 lying in a common plane as shown in Fig. 2. The base 40 plate 1 is suitably secured to the casing 2 at that point where the flange 5 extends from

the conical portion of the casing as shown. In its use this trap is placed over the ant burrow with its central opening α surrounding the burrow while the peripheral flange 5 is embedded into the earth so as to bring the base plate 1 into as close a contact as possible with the earth surrounding the ant hole above. When so arranged the opening α presents the only means of escape and the 50 ants coming out of the burrow will travel up the inverted frusto-conical inner member 4 and in attempting to escape therefrom will fall into the trap proper and by virtue of the inclined inner walls of the casing will be 55 trapped as they will be unable to climb up the same as the inner wall of this casing 2 will present a smooth surface; and

Having thus described my said invention what I claim as new is

As disclosed, an ant trap comprising the combination with a centrally perforated plate, of an inverted sheet metal frusto-conical member having its reduced end secured to said plate proximal to said perforation, 60 and a sheet metal frusto-conical casing having a peripheral cylindrical knife edged flange and an upper horizontally disposed flange, said plate being secured within said frusto-conical casing at the point forming the 65 union of said peripheral flange and conical portion, the upper end of said inverted frusto-conical member terminating in a plane coincident with the plane of said horizontal flange as described.

In testimony whereof, I affix my signature, in presence of two witnesses.

MARTIN T. HOWARD.
